UNITED STATES PATENT OFFICE.

ALFRED D. EDWARDS AND GEORGE H. ABBOTT, OF ELGIN, ILLINOIS, ASSIGNEES TO WOODRUFF & EDWARDS CO., OF ELGIN, ILLINOIS, A CORPORATION OF ILLINOIS.

ADJUSTABLE PEDESTAL FOR COMBINED DESKS AND SEATS.

Application filed December 31, 1923. Serial No. 683,562.

To all whom it may concern:

Be it known that we, ALFRED D. EDWARDS and GEORGE H. ABBOTT, both citizens of the United States, and residing at Elgin, in the county of Kane and State of Illinois, have invented certain new and useful Improvements in Adjustable Pedestals for Combined Desks and Seats, of which the following is a specification.

This invention which relates generally to furniture has particular reference to school desks and seats of the kind which use a standard in pedestal form, the purpose being to provide a serviceable, ornamental, and dependable device of this character on which may be mounted for plus and minus vertical adjustments a seat, as well as a desk, many of the parts being interchangeably constructed.

An exemplification of our invention is set forth in the accompanying drawing wherein—

Figure 1 is a side view, partly in elevation and partly in section, of the standard, together with seat and desk brackets mounted thereon; and

Figs. 2 and 3 are enlarged fragmentary details in section taken, respectively, on lines 2—2 and 3—3 of Fig. 1.

The major elements of this invention comprise a standard or support in the form of a pedestal A on which are mounted seat and desk brackets B and C, respectively. It is contemplated that suitable seat and desk fixtures (not shown) will be secured to the brackets when the furniture is ready for use. As shown, the cross sectional contour of the walls forming the standard is elliptical with its long axis extending from front to rear, and from the lower standard end which is flared outwardly to provide a base 5, these walls taper inwardly toward the upper end which is closed by a top or cross wall 6. A vertically extending slot 7 is formed in the front wall of the pedestal as is also a similar slot (not shown) in its rear wall, these two slots extending for a substantial substance in the middle region of the standard. The general construction of the standard and its two brackets, as described above, forms no part of this invention, but is made the subject of our prior application above referred to.

The seat bracket may consist of companion castings having a suitable configuration on their top for the support of a seat fixture per se. The walls of this bracket are extended downwardly therefrom and rearwardly toward the tapering front side of the pedestal. The bracket sides 11 each extend toward the pedestal and provide between them an open space such that their rearward edges 12 are adapted to bear against the standard at widely separated points. It will be noted from an inspection of the desk bracket C in Fig. 1 which, in all substantial respects, is the same as the seat bracket, that the rearward edges 12 which engage with the standard are also slanted in conformity with the taper of the pedestal walls, this relation being preserved in all the various different positions of vertical adjustment.

The bracket may be held against lateral shifting upon the pedestal by providing on the latter some sort of an element such as a rib or spline 13, located preferably just above and below the slot 7, this element co-operating with a complementary groove 13^a formed on the bracket. By some such co-operating means as these, the bracket is guided in its adjusting movements with independence of any other elements. Due to the chambered construction of the bracket which, in this respect, is like that of the supporting standard, the slot 7 is concealed in all positions of vertical adjustment of the bracket, its walls being properly dimensioned for this purpose.

We prefer to form each of the brackets of two complementary cast sections whose meeting edges are in substantial alignment with the plane which coincides with the long axis of the standard. As shown in the drawing, the two sections thus uniting to form the bracket are designated as 14 and 15. Formed at intervals on the section 14 are lugs 16 lapping past the juncture line 17 formed by the meeting edges of the two sections, and other similar lugs 18 are extended from the section 15 at intervals to lap past this juncture line, as best shown in Fig. 2. A very few of such lugs will suffice to hold the two sections against relative shifting movements either in a direction which is vertical or toward or away

from the standard, the lugs being preferably grouped in pairs and in engaging relation. With the sections thus assembled, we employ tie rods 19, as many as may be necessary, to connect them fixedly together.

For securing the two brackets upon the pedestal in any desired position of adjustment, we provide for each means as follows: A bolt 20 is inserted through a suitable lateral opening formed in the seat bracket front wall which may be thickened, as required, to provide adequate strength, the bolt head 21 being rested against the outer side of the bracket so as to be engageable by a socket wrench or other tool. The bolt shank engages with a nut 22 whose body is adapted to lie within the slot 7, the inner body end having a head 23 which bears against the inner face of the pedestal walls adjacent the slot. By turning the bolt to draw the nut thereupon, the bracket may be clamped upon the pedestal with a desired pressure. The nut is further formed on its outer end with a foot 24 in co-operative relation to a pair of webs 25 which extend toward each other, one from each section 14 and 15 of the bracket. These webs, together with other similarly extending walls 26, constitute for the bracket a rearward wall which lies adjacent to the front wall of the pedestal.

In the assembly of the brackets upon the pedestal the bolt 20 and nut 22 are first secured loosely in place. In order that the nut may take up the position shown in Fig. 1, we have provided between the webs 25 and walls 26 a clearance 27 sufficient for the insertion of the foot end of the nut. The nut body may thereupon rest against the lower edges of the webs to provide support for the bracket. Additional supporting means, which is also adjustable, we provide by a vertically extending bolt 30 which lies interiorly of the pedestal, the head 31 of this bolt resting exteriorly thereof on the cross wall 6. This latter bolt engages within a second threaded opening 32 formed in the head portion of the nut, the axis of this latter opening being transverse to that wherein the bolt 20 is received. By the use of an appropriate tool, such as a socket wrench, the bolt 30 may be rotated to raise or lower the nut 22 whenever the bolt 20 is sufficient loosened for this purpose. When the bracket is adjusted to the desired position, this latter bolt is then manipulated to draw the nut outwardly with the result that the bracket is clamped tightly upon the pedestal in a manner to avoid all play or movement thereupon. When so adjusted, the support of the bracket will be effected through the vertical bolt 30 in conjunction with the nut 22 upon whose body the webs 25 are rested. Preliminary to reaching this final adjustment, however, the foot 24 facil-

tates the retention of the parts in their assembled relation, and for this reason constitutes a desirable feature of our invention.

The parts just described are duplicated for the desk bracket and accordingly like reference numerals might be applied to the corresponding set of elements used in connection therewith. These adjusting parts are furthermore interchangeable such that either set may be used for the operation of the other bracket. In addition, either bracket may be changed around to occupy the position of the other since the pedestal formation is duplicated on both its front and rear sides.

In the raising and lowering movements of the two brackets, it will be noted that each is independent of the other. A plus and minus adjustment is provided for, however, due to the sloping character of the front and rear walls of the pedestal, so that as the seat is raised, it is also moved rearwardly. In like manner the desk is moved forwardly as it is raised. With an opposite adjustment of the two brackets, a reversal in these lateral movements is obtained. These changes in adjustment may be effected conveniently with the aid of a socket wrench, and the parts to be manipulated are sufficiently accessible to not require any change in position of the occupants. In addition the furniture article of our invention may be adjusted through a range sufficient to adapt the structure to persons of various sizes, and for accommodating persons of all ages only two sizes of the article will ordinarily be necessary.

A combined seat and desk of the kind described may be produced at a reasonable cost. In appearance it is attractive and the few places where dust, etc., may accumulate are easily reached for cleaning so that the article is advantageous from a sanitary standpoint as well.

We claim:

1. In a furniture article of the kind described, the combination of a standard having a vertically-slotted wall, a bracket having an apertured wall adapted to lie adjacent the slotted wall of the standard, a nut extending through the apertured and slotted portions of the two walls, means on opposite ends of the nut adapted to engage with the remote side of said walls, and screw-threaded means engaging the nut in a manner to support the same together with the bracket thereon in a desired position of vertical adjustment upon the standard, substantially as described.

2. In a furniture article of the kind described, the combination of a standard having a wall wherein is a slot, a nut positioned in the slot adapted to be moved lengthwise thereof, screw means associated with the nut and resting against a fixed portion of the

- standard for supporting the nut in a selected position of adjustment, a bracket associated with the standard having an apertured wall adjacent the nut, the nut being adapted for extension through the apertured wall of the bracket to support the same, means extending laterally from the nut end on the side of the bracket wall which is remote from the standard adapted to maintain the nut in assembled relation with the bracket, and other screw means connecting the bracket with the nut, substantially as described.
3. In a furniture article of the kind described, the combination of a bracket having front and rear walls, the latter of which is apertured, a nut extended through the rear wall and providing a support whereon the bracket is rested, a bolt entered through the front wall of the bracket and engaging the nut, a standard whereon the bracket is adjustably mounted, the standard having adjacent the bracket a slotted wall through which one end of the nut is extended, the nut end remote from the bracket being formed with a head adapted to engage with the side of the standard wall which is remote from the bracket, and a bolt mounted in the standard and extended parallel to its slotted wall with its threaded shank in screw threaded engagement with the nut head in a manner to raise and lower the nut together with its associated bracket, substantially as described.
4. In a furniture article of the kind described, the combination with a standard one wall of which is vertically slotted, of a bracket adapted for adjustable mounting upon said standard wall, screw threaded means connecting the bracket adjustably to the standard and extending in part through the slotted wall of the latter, the bracket being formed of two cast sections having a line of juncture which coincides with the standard slot, there being interengaging elements extended from one section inlapping relation to the other to secure the two sections against relative movement, other means for tying the two bracket sections together, and a web extended from each bracket section toward the other in overlying relation to the nut whereon the bracket is supported, substantially as described.
5. In a furniture article of the kind described, the combination of a standard, a nut slidably secured to one wall of the standard and extending in part exteriorly thereof, a bracket adjustably mounted on the standard, a bolt extended transversely from the standard connecting the bracket to the nut and adapted to tighten the bracket upon the standard, and means independent of the bolt for supporting the bracket on the nut, substantially as described.
6. A furniture article of the kind described comprising a supporting standard in the form of a pedestal having a base at its lower end and front and rear walls extending upwardly therefrom each tapering toward the other and connected by a cross wall, a seat bracket adapted for mounting on the front wall, means for preventing lateral movement of the seat bracket upon its mounting, a desk bracket adapted for mounting on the rear wall of the standard, means for preventing lateral movement of the desk standard on its mounting, interchangeable means for adjustably securing the seat and desk brackets upon their respective mountings comprising in each instance a member adapted to slide upon the inner side of the front wall of the standard and formed with a head adapted to bear thereagainst, there being a vertical slot in the standard through which a portion of the member extends, the member being further provided with two threaded openings, the axes of which lie in intersecting planes, a bolt passing through one wall of the bracket to engage with one threaded opening, the bolt head remaining exteriorly of the bracket, and a second bolt passing downwardly through the cross wall of the standard to engage with the other threaded hole of the member, the latter bolt being adapted to raise and lower the bracket upon the standard and the other bolt to clamp the bracket tightly against the standard, substantially as described.
7. In a furniture article of the kind described, the combination of a standard the walls of which are vertically slotted, a member having a head adapted to rest against the inner side of the standard walls and to present a portion of its body through the slot, there being formed in the member a pair of threaded openings, a bolt engaging within one opening and extending upwardly therefrom, means on the standard against which the bolt head is rested, a second bolt engaged within the other opening in the member and extending laterally from the standard, and a bracket formed to co-operate with the standard having a supporting connection therewith through the medium of the lateral bolt which is adapted to clamp the bracket upon the standard with a variable pressure, substantially as described.
8. In a furniture article of the kind described, the combination of a standard having front and rear tapering walls and a cross connecting wall, a pair of brackets one mounted to bear only on the front wall and the other to bear only on the rear wall, a pair of bolts entered through the cross wall, a single bolt entered through one wall of each bracket, a member bearing against the inner side of the front wall of the standard and arranged to co-operate with the bracket bolt as well as with one of the cross wall bolts, and a second member bearing against the inner side of the opposite wall of the

- standard with which the other two bolts co-
operate, the two cross wall bolts being adapt-
ed to effect vertical adjustments in the
brackets and the other two to clamp the
brackets tightly against the standard in any
given position of adjustment, all of the bolts
being independently operable whereby either
bracket may be adjusted without reference
to the other, substantially as described.
- 10 9. In a furniture article of the kind de-
scribed, the combination of a standard the
walls of which are vertically slotted, a mem-
ber having a head adapted to rest against
the inner side of the standard walls and to
present a portion of its body through the
slot, there being formed in the member a
pair of threaded openings, a bolt engaging
within one opening and extending upwardly

therefrom, means on the standard against
which the bolt head is rested, a second bolt 20
engaged within the other opening in the
member and extending laterally from the
standard, a bracket formed to co-operate
with the standard having a supporting con-
nection therewith through the medium of 25
the lateral bolt which is adapted to clamp
the bracket upon the standard with a vari-
able pressure, and co-operating means on the
bracket and standard for positively prevent-
ing lateral movement of the former relative 30
to the other, substantially as described.
